PRESSURE-ATOMIZING TYPE OIL BURNER
HAVING A HIGH-FREQUENCY VIBRA-
TORY-PISTON OIL-SUPPLY PUMP

Philip H. Bills, Longmeadow, Joseph A. Logan, Hadley, and Theodore J. Mesh, Easthampton, Mass., assignors to Gilbert & Barker Manufacturing Company, West Springfield, Mass., a corporation of Massachusetts

Application January 30, 1952, Serial No. 269,077

3 Claims. (Cl. 158—76)

1

This invention relates to an improved oil burner having a mechanical or pressure atomizing nozzle, supplied with liquid by a reciprocating-piston pump, which is controlled by an electro-magnet, supplied with alternating current through a half-wave rectifier, so that the pump piston is reciprocated at the frequency of the alternating current, say for example, 3600 cycles per minute.

This application is a continuation in part of our application, Serial No. 189,741, filed October 12, 1950.

The use of a pump of the type described as an oil supply means for a mechanical or high-oil pressure atomizing nozzle has many important advantages over the conventional rotary pump, heretofore used for the purpose in connection with oil burners adapted for house-heating service. Oil is pumped only at the rate that it is consumed; the pump is self priming; no cut-off or by-pass valves are required to respectively limit the minimum and maximum pressures at which oil is supplied to the nozzle; the pump stops instantly, when the power is cut off, thereby affording a quick cut-off of oil from the nozzle; a large saving in power is effected; the pressure of the oil supplied to the nozzle and the energy imparted to such oil is easily and conveniently varied by varying the voltage applied to the electro-magnet which actuates the pump.

The invention has for an object the provision of improved means for mounting a high-frequency vibratory-piston oil-supply pump on an oil burner of the pressure-atomizing type.

This and other objects will best be understood from the detailed description of one illustrative example of the invention in the accompanying drawings, in which:

Fig. 1 is a side elevational view of an oil burner embodying the invention;

Fig. 2 is a sectional elevational view taken on the line 2—2 of Fig. 3 and drawn to a larger scale;

Fig. 3 is a rear elevational view of the burner;

Fig. 4 is a fragmentary cross sectional view taken on the line 4—4 of Fig. 1;

Fig. 5 is a sectional plan view taken on the line 5—5 of Fig. 1;

Fig. 6 is a sectional elevational view taken on the line 6—6 of Fig. 3;

Fig. 7 is a cross sectional view taken on the line 7—7 of Fig. 6;

Fig. 8 is a diagram of the electrical connections of the burner;

Fig. 9 is a side elevational view of the burner, showing a modification in the fuel feeding means;

2

Fig. 10 is an enlarged fragmentary sectional elevational view of the pump, showing a diaphragm and chamber therefor connected with the outlet of the pump;

5 Fig. 11 is a full-size tracing taken from the screen of an oscilloscope and showing the form of the oil pressure wave developed by the pump, when operating alone, without any pulse-absorbing means or flexible tubing between the pump and nozzle;

10 Fig. 12 is a similarly-made tracing showing the effect on the oil pressure wave, when a certain length of copper tubing is introduced between the outlet of the pump and the nozzle; and

15 Fig. 13 is a similarly-made tracing showing the oil pressure wave when the diaphragm of Fig. 10 and the copper tubing shown in Fig. 9 are used between the outlet of the pump and the nozzle.

20 Referring to these drawings, the invention will be disclosed with reference to its use in an oil burner structure. For other uses, where combustion of the sprayed liquid does not occur and it is merely desired to spray the liquid, the air-supply and ignition provisions, hereinafter disclosed, may be omitted.

25 In these drawings, a gun-type oil burner has been disclosed which, in general, is of well known form, although it embodies occasional improvements in the burner structure and, of course, the novel fuel supply and atomizing means of this invention.

30 Referring first to Fig. 6 thereof, the burner includes an air-supply fan 1, mounted in a casing 2, which is suitably supported as by a floor plate 3 and an adjustable post 4. Casing 2 (see Fig. 4) has openings 5 and 5' in opposite end walls 6 and 6', respectively, and a peripheral outlet 7 (Fig. 6) leading into an air chamber 7', which overlies

35 the fan and to which one end of a tube 8 is connected. This tube conducts all the air for combustion and has its other end open and adapted to discharge into a furnace. Near the discharge end of tube 8 is a high-oil-pressure atomizing nozzle 9 of the usual well known form for producing a spray, when supplied with oil or other liquid under a pressure greater than a predetermined minimum value. On the outer end of the tube 8 is an air director 10 for turning the air stream into the spray of atomized oil emitted from the nozzle. In the tube is a turbulator for

40 whirling the air prior to its mixing with the oil spray, such turbulator comprising a series of spiral vanes 11 projecting inwardly from an annular ring 11'. The opening 5 in the fan cas-

ing (Fig. 4) receives a frusto-conical air director 12, the flanged outer end of which is clamped to end wall 6 by a ring 13, secured by screws 14 to such wall. The opening 12' within the air director 12 forms the main air inlet for the fan. The other opening 5' is covered by a plate 15, which is secured to end wall 6 by screws 16 and which has a plurality of openings 17 therethrough. The fan 1 has its hub fixed, as indicated, to the shaft 18 of an electric motor 19. The latter is fixed to the described plate 15 by screws 20, which pass through the plate and thread into lugs 21 on the inner end wall 22 of the motor. Between these lugs and the end wall are passages 23, leading to the openings 17 and thus to the interior of the fan casing. Thus, air is drawn in by the fan 1, partly through the main inlet 12' and partly through the auxiliary inlet, comprising the passages 23 and holes 17, and forced out through outlet 7 (Fig. 6) into chamber 7' and from the latter through tube 8, the air being whirled by the turbulator vanes 11 and just before it is directed by cone 10 into the spray of atomized oil emitted from the nozzle 9.

The particular motor shown is a very small one, say for example, a one thirty-fifth horse power, split-phase, 115 volt, 60 cycle, alternating-current motor. It customarily has ventilation openings in both end walls and a ventilating fan (not shown) fixed to its shaft inside the casing. Motors of this type tend to run rather hot and it is desirable to space the inner end wall 22 from the plate 15, to which it is fastened and provide for a flow of cooling air along this inner end wall. Such air, warmed by the heat exchange with the motor, is drawn in by the fan, as above described, and utilized for combustion.

The rate, at which air is supplied to tube 8, is variable by adjustment of a damper 24 (Fig. 6), mounted on a pivot rod 25, fixed at its ends (Fig. 4) in the walls 6 and 6' and movable by turning a screw 26 (Fig. 6). The latter passes through casing 2 and is threaded in a nut 27, swivelled in the damper. The head of the screw is held against the outer face of casing 2 by a spring 28, mounted on the screw and acting between the inner face of the casing and a collar 29, fixed on the screw.

The oil is supplied to nozzle 9 by an electro-magnetically - operated reciprocating - piston pump which is mounted on one side wall of the casings 2, as shown in Figs. 1, 3 and 5. This pump and the electromagnet, which actuates it, are mounted in a casing, comprising a main section or body 31 and a cover 32. The lower end of the body and the upper end of the cover are respectively provided with shoulders 33 and 34 and hubs 35 and 36, projecting in opposite directions one from each of the shoulders. A grommet 37, of rubber-like material, encompasses each hub and abuts the adjacent shoulder. Each grommet (Fig. 5) has a circumferential groove in its outer periphery to receive a part of a supporting arm 38 and a U-shaped clamp 39, which is fixed at its ends to the arm by bolts 40. Both arms 38 (Fig. 3) project outwardly at right angles from a common support 41, which is fixed to casing 2 by screws 42.

Referring next to Fig. 2, the body 31 of the pump and its cover 32 are made of suitable magnetic material, and as shown of cast iron. The upper portion of body 31 has a large cylindrical recess in which is mounted the annular coil

43 of the electromagnet. Body 31 has a hole coaxial with the magnet coil recess and extending from the latter through the body to the bottom thereof and fixed, as by a drive fit, in this opening is a rod 44, which is also of suitable magnetic material and in which is formed the cylinder 44' of the pump. Rod 44 has an integral upward extension 45 projecting through the central opening in coil 43 and forming the core of the electromagnet. Slidable in cylinder 44' is a piston 46, which extends upwardly through core 45 and has fixed to its upper end at a location above the upper end of the core, an armature 47. The latter preferably has a frusto-conical lower end to cooperate with a complementary-shaped recess in the upper end of the core 45. The frusto-conical face of armature 47 preferably has a series of brass inserts 47' which project outwardly from its face a small amount, preventing contact between the two cooperating magnetic faces and sticking of such faces, one to the other, by residual magnetism. The cover 32 has a central opening 48 therein, which slidably receives the armature, and in this opening are a series of angularly-spaced longitudinally-extending grooves 49 to allow liquid to pass the armature. A spring 50, which is located in opening 48, acts between suitable seats, one on the end wall of the opening and one on the top of the armature and encircling rod 46, and tends to move the armature downwardly. A similar spring 51, mounted at its ends in suitable seats in recesses in the bottom of the armature and the upper end of core 45, tends to move the armature upwardly. The armature is balanced between these two springs, which have the same dimensions and are under the same initial stress. The armature is shown in its rest position midway of its stroke. The mass of the armature 47 and rod 46 and the characteristics of the springs 50 and 51 are so selected as to have a natural period of vibration substantially equal to the frequency of the alternating-current supply to which the coil 43 is adapted to be connected. As shown diagrammatically in Fig. 8, the coil 43 is adapted to be connected to a 115 volt, 60 cycle, alternating current source through a suitable half-wave rectifier 52, which may, for example, be a selenium cell rectifier. Thus, when the control switches, indicated in the diagram and later to be described, are closed, the coil 43 will be energized intermittently in pulses at the rate of 3600 per minute. When coil 43 is energized, the armature 47 (Fig. 2) will be drawn downwardly toward the core 45 to actuate piston 46 on its pressure stroke, the magnetic circuit extending through core 45, across an axial air gap to armature 47, through the latter and across a small radial air gap to cover 32, outwardly through the cover in radiating paths to the annular shell which surrounds coil 43, downwardly through this shell and thence inwardly in radiating paths to the lower end of core 45. When coil 43 is deenergized in the interval between two successive energizing electric pulses, the armature 47 will move away from core 45 to and above the rest position illustrated. The stroke of the pump is variable, depending on the power applied to the coil and the resistance encountered by the piston. The resonant springs 50 and 51 serve to keep the armature 47 and piston 46 in vibration with only a small amount of assistance from coil 43, leaving the major part of the energy developed by the coil for the performance of useful work.

The pump cylinder 44' has an inlet port 53, communicating with a passage 54, which is formed in body 31 and extends horizontally outward and thence vertically upward to a cylindrical space 55, formed in cover 32 and located above coil 43. This space is connected by the described passages 49 and hole 48 to the oil inlet 56, which connects with the hole 48 by means of the central opening through the upper seat of spring 50. This inlet is connected by a suitable conduit, such as copper tubing 57, to a suitable oil supply tank (not shown), the tubing preferably having a coil 57' therein (Figs. 1 and 3). The coil 43 (Fig. 2) is suitably sealed off from the oil-containing chamber 55, as by a circular member 58, which closely fits around core 45 and the peripheral wall of the coil-containing recess and has inner and outer seal rings 59 to engage such core and wall. The pump cylinder is provided with a check valve in its outlet, such as the ball valve 60, which is held closed by a spring 61, acting against a seat on the upper end of a screw 62. The latter is threaded into the lower end of member 44 and closes the lower end of the opening therein. The outlet valve 60 opens into an outlet chamber 63, formed in member 44, and this chamber connects with an outlet passage 64 formed in the body 31.

The outlet passage 64 delivers the pumped oil into a cylindrical chamber 65, formed in the lower part of body 31. A cover 66, secured to the body by screws 67, provides access to the chamber and has a central tapped opening therein which receives an outlet pipe 68. Within the chamber 65, is a block 69 of suitable resilient material, which in this case, is composed of particles of ground cork held together by a rubber-like binder. The block is square in cross section and its four longitudinal corner edges engage the cylindrical wall of chamber 65, leaving four longitudinal passages for the oil. Protuberances 70 on the end walls of this chamber engage the ends of the block and hold them spaced from the end walls to enable oil from passage 64 to flow outwardly to said longitudinal passages and thence inwardly from the latter to the outlet pipe 68. One purpose of this arrangement is to smooth out the pulsations in the stream of pumped oil. The pressure of the pumped oil will vary in a wave which rises from a minimum to a maximum and back again at the frequency of the alternating-current. The higher instantaneous pressures will compress the member 69 and, at the lower instantaneous pressures, the member 69 will expand. Thus, the peaks of the wave will be removed and the valleys filled in so that the stream leaving through pipe 68 will not have such wide fluctuations in pressure. A very important purpose of the described arrangement is to keep the minimum instantaneous pressure of the oil stream above the lower pressure limit of the atomizing nozzle 9. As is well known, if the pressure of the oil fed to a pressure or mechanical atomizing nozzle falls below a certain critical value, the nozzle will not produce a spray. Hence, it is essential to provide a limiting means which will maintain minimum pressures above this critical value and high enough to insure that the nozzle will be operative to produce a safe and stable spray under all conditions usually encountered in practice.

The pipe 68 delivers the oil stream into a pressure-regulating device, which is contained in a casing 71, having a cover 72, held in place by screws 73. The pipe 68 is connected to the end 75

of casing 71, opposite from the cover, and opens into a passage 74, having a counterbored part, in which is located a ball 75. This ball is not a valve in the usual sense because it never closes in normal operation. Rather it is an obstruction, which may be variably positioned to variably restrict the effective area of the passage 74, accordingly as variations in pressure of the pumped oil occur. Voltage variations in the alternating-current supply will cause variations in pressure of the pumped oil. The pressure varies directly with the voltage and, in the present example would vary about four pounds per square inch for each change of one volt in the voltage of the alternating current supply. It is necessary, therefore, to compensate for fluctuations in line voltage, which might under some circumstances render the nozzle inoperative and in others would cause too wide variations in the firing rate for satisfactory operation. The obstruction 75 is one way of compensating for such voltage variations and thereby maintaining the oil pressure at the nozzle within acceptable limits. By oil pressure, is meant the pressure, which shows on a gauge, that is average pressure. The obstruction ball 75 is moved by a plunger 76, fixed to one end of a rectangular frame 77. The other end of this frame has fixed thereto one end of a closed bellows 78, containing a spring 79, tending to separate the ends of the bellows. The other end of bellows 78 is fixed to one end of a second rectangular frame 80, the other end of which is fixed to the cover 72, and, as shown, by means of a screw 81, threaded into an opening in cover 72. The frame 80 has openings 80' to slidably receive one end of frame 77 and limit its movement toward ball 75. The outer end of such opening is closed by a screw 82. By removing screw 82, screw 81 may be turned to vary the position of frame 80 and thus the force exerted by spring 79 tending to expand the bellows and draw plunger 76 to the left to decrease the restriction in passage 74. In the example herein shown, the bellows will not be contracted until the oil pressure reaches 100 pounds per square inch and ball 75 presents the least restriction. This is the position of the ball for the low limit of voltage regulation, say for example 100 volts. Increase in the line voltage causes the pump to develop more pressure which tends to contract the bellows and move the frame 77 and plunger 76 to the right to increase the restriction of passage 74 and cause a greater pressure drop in the oil. On a decrease in the voltage supplied to coil 43, the pump will develop less pressure and the variable obstruction 75 will be moved to the left to decrease the restriction in passage 74, decreasing the pressure drop and thereby increasing the pressure of the oil supplied to the nozzle. The obstruction would be in its mid position at normal voltage, say for example, 115 volts, and would move to the right or left to increase or decrease the restriction as the voltage rises or falls respectively. With this arrangement, the pressure of the pumped oil may be maintained substantially constant over a range of voltage variations from 100 to 130.

As shown, a light spring 83, acts between the ball 75 and a shoulder on plunger 76, but this spring is not strong enough to move the ball against the seat in the counterbore of passage 74 during normal operation. It merely prevents the ball from rattling.

The outlet of the pressure-regulating device is connected by a suitable conduit to the atomiz-

ing nozzle 9. As shown, this conduit includes a copper tube 84 (Fig. 1), which extends upwardly from the outlet of the regulator, has a coil 84' formed therein and then enters through a notch in the side wall of casing 2 into the rear end of the chamber 7', where it extends forwardly, as shown in Fig. 5, and is connected by a union 85 to the rear end of a tubular and oil-conducting support 86. The nozzle 9 is connected to the front end of this support.

Adjacent the nozzle 9 are a pair of electrodes 87, which are mounted in insulators 88 and have their rear ends connected by wires 89 with the high tension terminals 90 (Fig. 6) of an ignition transformer, mounted in a case 91, fixed on top of casing 2.

The nozzle 9, turbulator 11-11', and electrodes 87 may be supported in any suitable way in tube 8, desirably in the manner indicated in Fig. 5, to permit convenient withdrawal of these parts in assembled relation from the tube 8 and the aligned chamber 7', after the closure plate 92 for the rear end of chamber 7' and its retaining screws 93 have been removed. To this end, a pair of rods 94 are fixed at one end to the ring 11' of the turbulator, one at each of two diametrically opposite points thereon, and these rods extend rearwardly in spaced, parallel relation through tube 8 and through chamber 7', terminating in outwardly-bent parts 95, the outer ends of which are received one in each of two notches formed one in each of two opposite side walls of the casing 2. The plate 92 retains these ends 95 in their notches. Fixed at its ends to rods 94 and spanning the space between them, is a support 96 having a central hub, in which the nozzle-supporting tube 86 is fixed, and two upper hubs in which the insulators 88 are fixed. The support 96 also has a central depending hub, to which an air-distributing baffle 97 is fixed. It will be clear that when plate 92 is removed, the ends 95 of rods 94 are released. The high tension wires 89 will then be disconnected from terminals 90 and the oil pipe 84 will be disconnected by removing union 85 or 85', after which the nozzle 9, its support 86, the electrodes 87 with their insulators 88 and the turbulator 11-11' may be withdrawn for inspection, cleaning or repair.

The invention includes a control switch 98 for the coil 43 of the electromagnet. As shown in Fig. 8, this coil, the switch 98, the half-wave rectifier 52, and a variable resistor 99 are included in series in a circuit 100 which is shunted across the wires 101 and 102 that supply the fan motor 19 and the primary 103 of the ignition transformer, the secondary 104 of which is connected by the described wires 89 to the ignition electrodes 87. Any suitable control may be provided to start and stop the motor 19 and ignition transformer and such a control has been indicated, simply and schematically, by a thermostat switch 105, which usually is responsive to temperature in the space to be heated and connects wire 101 to a wire 106, when there is a demand for heat. The wires 102 and 106 are adapted for connection to a suitable source of electricity, say for example a 115 volt, 60 cycle, alternating-current source. The electromagnet 43 is adapted to be energized only after the air supply has been well started by the motor. Therefore, the closing of switch 98 is delayed, as by a speed-responsive device to be described. When this switch is closed, the electromagnet will be energized intermittently in pulses at the fre-

quency of the alternating current. The resistor 107 is shunted across the rectifier to allow a small amount of current to flow to coil 43 in the intervals between the aforesaid pulses for the purpose of demagnetizing the core to avoid possible sticking of the armature thereto.

The switch 98 is shown in Figs. 1 and 4 as a micro-switch, mounted on an angle-iron shelf 108 fixed to the end wall of a cylindrical case 109, having its other end closed by a disk cover 110, secured by screws 111 to the case. This case 109 is supported by four angularly-spaced arms 112 from the described ring 13, leaving openings 113 through which air may enter to the main inlet opening 12' of the fan. The switch 98 has an actuating plunger 98' and suitable spring means (not shown), tending to move the plunger to the left, as viewed in Fig. 4, into closed position. The switch plunger 98' is actuated by a plunger 114, which is slidably mounted in a hub on the end wall of case 109. This plunger 114 is shown held in its right hand and switch-opening position by the flanged and closed outer end of a tube 115, which is slidably mounted on a rod 116, having a flanged end, fixed as indicated to the drive shaft 18 of motor 19. A spring 117 encompasses rod 116 and acts between the flange on the rod and the adjacent end of tube 115 to force the latter to the right and press the plunger 114 and the plunger 98' of switch 98 to open the switch. The flanges of rod 116 and tube 115 are interconnected by flexible metal bands 118, each having fixed to it at a point between its ends a suitable weight 119. When the shaft 13 reaches a predetermined speed, as nearly as feasible to full speed of the motor 19, these weights 119 fly outwardly by centrifugal force and deflect the bands 118 outwardly, drawing tube 115 to the left until it allows the plungers 114 and then 98' to move to switch-closing position and continuing until it disengages from the plunger 114. A small spring 120 takes up the lost motion and holds plunger 114 in contact with plunger 98' and out of contact with the outer end of the rotating tube 115. Spring 120 is not strong enough to move the switch plunger 98' against its internal actuating spring (not shown).

In operation, the rate of flow of oil from the nozzle 9 is controlled by varying the power applied to coil 43, which may be done in any suitable way. As an illustrative example, the variable resistor 99 is shown for the purpose. With a selected size of atomizing nozzle, there will be a certain amount of load imposed on the pump and the power applied to the magnet is adjusted to that load. Preferably, the magnet is designed to operate the piston at slightly less than full stroke for the largest size nozzle to be used. Lesser rates of flow can then be secured by including more resistance in the circuit, as by means of the variable resistor 99. Slightly less than full stroke operation is desirable to avoid noise in operation. It should be noted that the nozzle selected does not have to be operated at the rate which is specified for it to be operated. The one size nozzle can be operated at different rates by varying the pressure of the oil supplied to the nozzle, such pressures being variable, as for example from a minimum of 75 p. s. i. to a maximum of 200 p. s. i. by varying the voltage applied to the magnet of the pump. Having selected the nozzle and secured the desired rate of oil flow, the rate of air flow is adjusted by means of screw 26. This adjustment may be made for a high percentage of CO₂ because the

oil flow is delayed until good air flow is produced in order to avoid smoky operation during the starting and stopping intervals of each run of the burner.

In normal operation, on a demand for heat from the burner, switch 105 closes and starts the motor 19, which drives fan 1 causing the latter to produce a flow of air through tube 8 and past the turbulator vanes 11. As soon as the fan nears full speed, the centrifugal switch 98 closes to connect coil 43 to its alternating-current supply, and the fuel pump is set in action. The ignition transformer may be energized with the motor 19, as shown, or it may be delayed until coil 43 is energized. With the pump in operation, oil is fed to nozzle 9 and emitted in a finely atomized conical spray. The air mixes with this spray and the mixture is ignited by sparks produced between the electrodes 87.

As differentiated from the common means of supplying oil to a mechanical atomizing nozzle, the stroke of the fuel pump is variable according to the load and according to the power applied. All of the oil pumped goes to and through the nozzle. Oil is supplied only at the rate it is consumed. None of the oil is by-passed, as is the case with the usual rotary pump driven at constant speed by an electric motor. There the pump is designed to pump oil at a far greater rate than it is used and all excess oil is by-passed. The rotary pump may by-pass as much as 17 gallons per hour all of which has to be raised to the high pressure say for example 100 p. s. i. There, a cut-off valve prevents flow of oil to the nozzle until a predetermined minimum oil pressure has been established and a relief valve opens a by-pass as soon as a predetermined maximum oil pressure has been established. There, wide fluctuations in line voltage would slow the motor, fan and pump but not so much as to lower the oil pressure below the critical lower limit at which the nozzle is inoperative to produce a spray.

With a pump of the character described, as the line voltage falls, the pressure of the pumped oil falls with it in direct proportion and may go all the way to zero or until the pump outlet valve closes and this outlet valve is provided merely as a check valve and not to establish a lower limit of oil pressure. Actually, in the present pump, operated with the described current and supplying a pressure atomizing nozzle rated at one gallon per hour (when operated at a pressure of 100 pounds per square inch, and without the voltage-pressure control herein disclosed), the oil pressure varied 4 pounds per square inch for each one volt change in voltage. The Underwriter's require safe operation of a burner at from 85% to 115% of normal voltage or from 98 to 127 volts, assuming normal voltage to be 115. A variation of 29 volts would mean a variation of 116 pounds in oil pressure which of course is altogether too great to be tolerated. The firing rate would vary widely and also the pressure might very well drop so low that the nozzle would cease to produce a good spray. Hence, the regulator disclosed is essential in a system of this kind. It is not a pressure-regulator of the ordinary type, in which a valve opens at a predetermined pressure and by-passes the excess oil to keep the stream pumped to the nozzle at a constant pressure. Such a valve would be useless here because the instant it opens, the pump is unloaded and goes to full stroke operation, becoming very noisy. What

the present regulator does is to compensate for variations in line voltage. As long as this voltage is normal, the regulator does not function. It comes into play only when the line voltage increases or decreases from normal and then it prevents the wide variations in oil pressure that would otherwise occur.

The burner shown in Fig. 9 is the same as that shown in Figs. 1 to 7 inclusive except that the regulator that compensates for variations in line voltage is omitted and the outlet of the pump is connected by a length of copper tubing 121 to one end of the tube 86 which carries on its other end the atomizing nozzle 9. Also, the pump, at its outlet end, is somewhat differently constructed, as will be explained. Variations in line voltage may be prevented from causing substantial variations in oil pressure by any suitable electrical regulator which will function to maintain constant current in the circuit of coil 43.

The electromagnetic pump is essentially the same as before but the chamber 65 and resilient member 69 have been replaced by a diaphragm 122 and a chamber 123, formed in the pump body 124 above the diaphragm and in communication with the outlet of the pump. As shown the marginal portion of this diaphragm is rigidly held by clamping it between a cap 125 and the body, the cap being suitably secured to the body as indicated. The upper face of the cap has a shallow conical recess 126 therein located immediately below the diaphragm. The cap is formed for mounting in the lower resilient grommet 37 in the same way that the lower portion of the pump body 31 of Fig. 2 was formed. The lower end of the member 44 stops short of chamber 123 and the plug 127, that is threaded into the lower end of member 44 to provide a seat for the spring 61 of the check valve 60 of the pump, has a passage 128 therethrough to connect the pump outlet to the chamber 123. The pump outlet passage 64 connects directly with the copper tube 121. Otherwise the pump is constructed and operates as heretofore described.

As one suitable example, the diaphragm 122, herein shown, is made of brass, has a thickness of .009" and the circular area that is exposed to oil pressure is 1 1/4" in diameter. The lower chamber 126 has the same diameter and its maximum depth is .027". The outlet of the pump is connected to the rigid nozzle supporting tube 86 by $\frac{1}{8}$ " copper tubing which has a length of 22 1/2".

The operation of the electromagnetic pump, when its outlet is connected directly to the inlet of an atomizing nozzle of the mechanical or high-oil-pressure atomizing type, without any substantial length of intervening conduit and without the pulsation-modifying means of this invention is illustrated in Fig. 11. The graph there shown is a tracing from the screen of an oscilloscope, arranged to show the oil pressure at the inlet of the atomizing nozzle. The nozzle used was one rated for 1 gallon per hour at 100 pounds per square inch. As will be seen, the pressure rises sharply on the pressure stroke, as indicated by the part 130 of the graph, from a minimum of 58.8 p. s. i. to a maximum of 141.2 p. s. i. and then decreases on the suction stroke of the pump, as indicated by the part 131 of the graph, to the aforesaid minimum. The very steep rise in pressure results in a severe impact, which tends to cause vibration in parts attached to the pump. A very wide variation in oil pres-

sure is produced, in this case plus or minus 41.2% from the average pressure of 100 p. s. i. indicated by the line 132 of the graph, or a total variation of 82.4 p. s. i. In particular, the minimum instantaneous pressure values are too low for producing what may be called a safe stable spray from a nozzle of the type described, where atomization is affected by the action of centrifugal force on the release of a very rapidly whirling oil stream. Merely to connect a mechanical atomizing nozzle directly to the outlet of the pump will not produce results, which are satisfactory for commercial use.

It is necessary, as a practical matter, to provide in an oil burner between the outlet of the pump and the atomizing nozzle a conduit of substantial length, and, usually, tubing which is somewhat flexible is used for the purpose because it may readily be bent to the form required. Usually, copper tubing is used for the purpose. The use of such tubing has an adverse effect on the operation of the pump and nozzle. Harmonics are produced in the pressure wave. Increases in length of the tubing cause resonance at decreasing orders of frequency. The spread between maximum and minimum instantaneous pressures increases with increases in length of the tubing. Fundamental resonance occurs with a tubing length of about 10 feet and the pressure variations then are substantially plus or minus 100%. Fig. 12 shows what occurs with the use of a 20 inch length of $\frac{1}{8}$ " copper tubing. The graph 133 shows a transition between the fourth and third harmonics with the wide spread in pressure variations of plus or minus 55.8%. The dotted line 134 is the estimated 60 cycle fundamental wave.

In Fig. 13, is shown the pressure wave as produced by the pump of Fig. 10, as above defined, and a $22\frac{1}{2}$ " length of $\frac{1}{8}$ " inch copper tubing between the pump outlet and the nozzle, which is rated at 1 gallon per hour at a pressure of 100 pounds per square inch. The diaphragm 122, having the dimensions above set forth, modifies a pressure wave very similar to that shown in Fig. 12 so that the pressure variations are substantially reduced to plus or minus 15.6% and in particular the minimum pressures are maintained well above the critical pressure at which a safe stable spray would be formed, as for example 65 to 70 pounds per square inch. The pressure wave 135 has three harmonics but their amplitude has been very greatly reduced. The dotted line 136 represents the estimated 60 cycle fundamental wave.

The diagrams of Figs. 11 and 12 illustrate operations of the electromagnetically-operated pump that are unsatisfactory for the purpose of producing a satisfactory spray from a nozzle of the mechanical or pressure-atomizing type. Fig. 13 clearly shows how the diaphragm 122 renders the operation of a high-frequency reciprocating-piston pump of the class described suitable for use as an oil supply means for a mechanical atomizing nozzle. The member 69 and chamber 65 will function in a similar way. The output of the pump normally is in the form of a saw-toothed pressure wave such as shown in Fig. 11 having amplitude which is excessive for the purpose and, in particular, minimum pressure values below those at which a safe and stable spray can be produced. The condition is made worse as shown in Fig. 12 by the use of the conduit that is necessary to connect the pump and nozzle. The difficulty is thought to be due in 75

part to the compressibility of the liquid in a conduit, presenting considerable volume between the pump and nozzle, and in part to the elasticity of the conduit itself. Elasticity at the outlet of the pump absorbs some of the vibrations from the severe impacts of the pressure strokes of the pumps and limits the adverse effects that would otherwise occur in the conduit intervening between the pump and nozzle. Controlled elasticity at the outlet of the pump is preferred. Elasticity, which is distributed along the conduit or at the nozzle is not as good because it tends to prevent the sharp cut-off that is desired, when the power to the pump is cut-off, in order to prevent after-squirt at the nozzle. The diaphragm 122 has been shown to provide the amount of elasticity located at the right place to smooth out the pressure wave of the pump and maintain the instantaneous minimum pressure values well above the critical pressure at which a safe and stable spray can be produced by the nozzle.

The invention thus enables a high-frequency reciprocating-piston pump to be used as a means of supplying liquid to a mechanical atomizing nozzle and very important advantages to be secured without the accompanying disadvantages, and even dangers, that otherwise might follow from low instantaneous pressure values and the resulting failure of the nozzle to produce an effective spray.

What is claimed is:

1. In an oil burner, an air-supply fan, a casing for the fan having inlet and outlet openings, a tube connected at one end to the outlet opening and conducting the air for combustion, a motor for driving the fan, a pressure-atomizing nozzle in said tube near the other end thereof, a reciprocating-piston oil-supply pump, a conduit connecting the pump to said nozzle, an alternating-current electromagnet connected to reciprocate said piston at the frequency of the alternating current, said pump having two spaced parallel shoulders and cylindrical hubs extending in coaxial relation in opposite directions from said shoulders, grommets of rubber-like material one encompassing each hub and abutting the adjacent shoulder, and a support on said casing having spaced parallel outwardly-projecting arms supporting said grommets one in each.
2. In an oil burner, an air-supply fan, a casing for the fan having inlet and outlet openings, a tube connected at one end to the outlet opening and conducting the air for combustion, a motor for driving the fan, a pressure-atomizing nozzle in said tube near the other end thereof; an oil-supply pump comprising a body having a cylinder with an inlet and an outlet, a piston reciprocable in said cylinder, a valve for closing the outlet, and a spring tending to hold the valve closed, a conduit connecting the outlet of the pump to said nozzle, an alternating-current electromagnet connected to reciprocate said piston at the frequency of the alternating current, said pump having two spaced parallel shoulders and cylindrical hubs coaxial with said cylinder and extending in opposite directions from said shoulders, two grommets of rubber-like material one encompassing each hub and abutting the adjacent shoulder, and a support on said casing having spaced parallel outwardly-projecting arms supporting said grommets one in each.
3. In an oil burner, an air-supply fan, a casing for the fan having inlet and outlet openings, a tube connected at one end to the outlet opening and conducting the air for combustion, a motor

for driving the fan, a pressure-atomizing nozzle in said tube near the other end thereof, a reciprocating-piston oil-supply pump; a conduit connecting the pump to said nozzle, an alternating-current electromagnet connected to reciprocate said piston at the frequency of the alternating current, said pump having two spaced parallel shoulders and cylindrical hubs extending in coaxial relation and in opposite directions from said shoulders, grommets of rubber-like material 10 one encompassing each hub and abutting the adjacent shoulder, each grommet having in its periphery a circumferential groove, and a support on said casing having spaced parallel outwardly projecting arms each having a semi-circular edge engaged in one part of said groove, a member hinged at one end to the outer end of each arm and having a semi-circular part engaged in another part of said groove, and a fastener for holding the other end of each said 20 member to its arm.
